ATTORNEY

UNITED STATES PATENT OFFICE.

JOSEPH KAUFMAN, OF NEW YORK, N. Y., ASSIGNOR TO AMERICAN SAFETY RAZOR CORPORATION, OF NEW YORK, N. Y., A CORPORATION OF VIRGINIA.

CONTAINER.

Application filed July 5, 1924. Serial No. 724,229.

My present invention relates generally to containers and to their association and coordinately to such an association of containers as will on the one hand suggest and drive home effectively the advertising and selling features of the article contained in one of them, and as will on the other hand give to the user of the article a physical evidence of the benefits resulting from its use.

10 As is well known, the development of self-shaving is more or less tied up with the development of what is known as the safety razor, of which there are numerous types on the market.

15 While the factors of convenience and cleanliness have had a great deal to do with the almost universal practice of men to shave themselves, the greatest factor that has resulted in its universal development, and 20 which factor has become of the greatest importance, is the saving resulting, particularly in view of the fact that the cost of shaving in establishments known as barber shops, has increased with the general rise in the 25 cost of all commodities and of service.

In order to bring home this factor of saving and consequently to increase the use of safety razors and their sale, slogans such as "Shave and Save" have been adopted to 30 put in as pithy and as attractive a way, the fact that by shaving oneself with an outfit the initial cost of which is relatively small and the upkeep of which is also correspondingly small, a relatively large saving can be 35 effected.

It is obvious that slogans such as "Shave and Save" have been presented to the individual hitherto by advertisements of various characters, which, however, do not generally bring home the effect thereof at the time desired, namely, just at the time when the user is actually shaving.

One of the objects of my invention, is to 40 form a razor case container of such a character that the slogan "Shave and Save" or its import, will be forcibly presented to the user of a razor contained in such case every time the individual uses such razor.

The human mind is limited, however, 45 more or less to the specific, and in calculating savings, the average person keeps in mind only the fact that a single shave costs, let us say, twenty cents at a barber shop, and that a similar operation at home, pro-rated 50 for a sufficiently long time, taking into con-

sideration the initial cost and the cost of replacement and upkeep, may be, say only two cents, thus giving a saving of eighteen cents. The average individual, however, does not sit down to calculate, and even after he has done so, does not keep in mind that while at each shave he saves eighteen cents, that in the aggregate, for a period of a year, the saving will run over and above \$60 and even where he does realize and 60 keep in mind this aggregate of saving, there is no actual evidence thereof as by a distinct segregated accumulation of such saving over a period of time.

Another important object of my invention 70 is the provision of such a character of case for the safety razor, which will not only at all times remind a man of the fact that he is saving by shaving himself and will suggest to him the fact that he permit 75 the savings to accumulate, but which will give him a physical arrangement whereby accumulations of such savings can be made so that at the end of any stated period, as for instance, at the end of six months or a 80 year, he can not only tell definitely what the total saving has been as against the total cost, but in addition he will have such saving in a segregated fund.

My invention further provides an association with a razor, of a money container, so that with each shaving operation there will be right at hand not only a reminder that the user has economized, but also a physical container in which the money so saved at 90 that particular shave can be put away and kept segregated.

Another important object of my invention is the provision of a new, useful, simple, 95 economically constructed and effective container, and more particularly one intended to associate containers having a single aim in view, one of which is to serve to receive a razor and the other to serve as a bank.

For the attainment of these objects and 100 of such other objects as may hereinafter appear or be pointed out, I have illustrated one embodiment of my invention in the drawings wherein—

Fig. 1 is a perspective view of the embodiment of my invention.

Fig. 2 is a section taken on line 2—2 of Fig. 1;

Fig. 3 is a section taken on line 3—3 of Fig. 2;

Fig. 4 is a section taken on line 4—4 of Fig. 3; and

Fig. 5 is a sectional view of a detail taken on line 5—5 of Fig. 2.

Upon viewing Fig. 1 of the drawing, it will be observed that the specific embodiment herein disclosed, simulates a book, and is provided with side walls and end closures. The side walls 10, 11 and 12 are preferably 10 made of a single stamping and are provided at their opposite ends with the flanges 13 and 14 continuous with these three sides and presented substantially at right angles thereto and parallel with each other so as 15 to form seats for the end closures to be more fully described hereinafter.

The fourth wall 15 is preferably made separate from the other three walls and is curved so as to simulate the curved back 20 portion of the book and is secured to the end walls 11 and 12 in any preferred or desired manner as by the flanges 16 and 17 bent from the walls 11 and 12 under the straps 18 and 19 cut and bent up from the 25 rear wall 15. The outer ends of these flanges 16 and 17 are preferably bent inwardly, slightly, so as to maintain the four walls more effectively in assembled relation.

The covers or end closures 20 and 21 are 30 each secured in hinged relation with the assembled side walls, preferably by each having a plurality of lugs or pintles 21', 22 and 23 extending therefrom, preferably in the plane of the cover or closure, these 35 pintles being received in the openings in the straps 24, 25 and 26. Three such pintles have been shown, and it is understood that this is merely for purposes of illustration as any desired or preferred number may 40 be employed. Adjacent the pintles 21' and 23, the end closures are further each provided with the lugs 28 extending preferably substantially at right angles to the pintles and arranged to engage with the 45 straps 24 and 26 so as to form stops for the end closures when such closures are moved into their open position. And upon viewing Fig. 2 of the drawing, it will be 50 observed that the straps are buckled upwardly or outwardly intermediate their ends, as shown at 28', 29 and 30, so that on the one hand, the end closures can be moved to a position substantially at right angles to that of the container proper, and 55 on the other hand, when the end closures are brought down into closed position, these upwardly bent portions 28', 29 and 30 will engage with the material of the end closures which are preferably made of a springy 60 sheet metal so as to place such closures and straps under tension when the closures are moved and locked in their closed position, as will shortly be described, so that when the end closures are released from their 65 locking position, they will spring upwardly,

slightly, under the upward pressure of these portions 28', 29 and 30 which are placed under compression when these closures are locked. I have employed these additional lugs only in connection with the two end 70 hinges since I have found that I not only attain in this manner the desired results, but also attain it symmetrically.

From the description thus far given, it will be understood that I have provided a 75 container which has hinged closures at its opposite ends and I divide this container into two compartments by associating therewith preferably the integral stamping, which has a vertical partition wall 35 of a 80 width to extend substantially across the width of the container and of a height to extend from top to bottom, from which vertical wall extend in opposite directions the wall members 36 and 37 of such length 85 that the member 36 extends from the partition wall 35 to a line closely adjacent the wall 11 and the wall member 37 extends in the opposite direction to the line closely 90 adjacent the wall 12.

It will therefore be understood that when this integral stamping forming the partition wall and wall members is assembled in the 95 container in the manner shown in Fig. 2, that the container is thereby divided into two compartments, one to the side of the other, one compartment, however, open at one face and the other open to the other face so that the closure 20 forms a closure for the compartment delimited by the walls 10, 12, 15 and 35, and the other closure forms a closure for the compartment delimited by the end walls 10, 11, 15 and the partition wall 35.

Fixed in spaced relation to the front wall 105 is the member 40 (see Fig. 2) and slidably in the guide channel formed between this member and the wall 10 are the latch bolts 41 and 42' which are generally 7-shaped in vertical cross-section, and these latches are 110 normally, yieldably maintained in their position adjacent each other in any preferred or desired manner as by the spiral springs 44 and 45 which have their inner ends attached to the opposite extreme ends of the member 40 and their outer ends each attached to the outer ends of the latch bolts 41 and 42 respectively.

The springs 44 and 45 and the slide latch bolts 41 and 42 are preferably symmetrically 120 arranged with reference to the longitudinal and vertical axes of the front wall of the container and are so proportioned as to present the turned abutments 46 and 47 at their inner ends adjacent an opening 48 in the front wall 10 which opening is of a character such as shown in Fig. 1 of the drawings, so that upon the insertion in this opening 48 of a key of appropriate design 125 and size and a rotation of such key, the abut- 130

ment ends 46 and 47 will be contacted with by the key and moved in opposite directions, carrying with them the slide latch bolts 41 and 42.

5 These slide latch bolts 41 and 42 are provided at their opposite faces, that is, on the legs of the U, with the latch members 50, the function of which I will now point out.

The cover 21 which closes the compartment on the right in Fig. 2 is preferably provided with the depending hasp members 53 and 54, each of which has the angled nose 55 at its lower surface (see Fig. 4) and the sharp shoulder 56 intermediate its ends, so that when the cover 21 is moved to its closed position, the angled surface 55 will automatically retract both latch bolts 41 and 42 until the point of the nose is reached, when the latch members will be drawn toward each other by the springs 44 and 45 and caused to position the latch member immediately above the wall 56 so as to lock the closure member 21 against opening. In this position of the closure 21 it will be impossible to unlock this closure 21, except by an operation of the key (not shown).

The opposite cover 20 is provided with latch members 60 and 61 which have at their outer ends the angled surface 62 which act in all respects substantially as do the surfaces 55 of the latch members 53 and 54 already described in connection with the cover 21, but instead of being provided with the straight walls 56, as in connection with the cover 21, are provided with the angled surfaces 63, so that when the cover 20 is moved to closed position, the members will act exactly as do the members 53 and 54, but due to the changed character of the surfaces 63, will permit this cover to automatically retract the latch bolts when ever it is desired to open this cover 20. In other words, the cover 20 which closes the compartment 70 can be opened and closed at will, merely by a movement of the cover toward and from the container, but the closure 21 for the compartment 71 can be opened only upon an operation of the key.

The compartment 70 is intended to contain an article of merchandise such as a safety razor outfit, as shown in Fig. 1 of the drawing, whereas the compartment 71 is intended to serve as a savings bank, and for this purpose the wall 11 is provided with an opening 74 of such a character as to permit of the insertion of coins and to make the savings bank more efficient, I have positioned adjacent the opening 74 and on the inside of the compartment 71 the spiral springs 75 and 76 spaced apart slightly less the width of the opening 74, these springs being longer than the opening 74 and being carried from the plate 77 which is mounted on the inside of the wall 11.

65 It will be understood from the description

thus far given, that I have provided a safety razor container, which is so constructed that anyone attempting to use the razor contained therein for shaving, will not only necessarily have brought to his attention the fact that there is a saving resulting from shaving himself, but also that such a saving should be deposited in the compartment 71 through the opening 74. In addition to this, the closures for this container are so constructed that while the closure for the razor compartment can be opened and closed conveniently and without difficulty, the closure for the savings bank can be opened only by the operation of a key.

In order to further carry out the book effect which it is desired that my invention shall preferably have, I provide both covers with a leather or leather-like facing 80, and to still further carry out this simulation, it will be observed that I have made the rear wall 15 not only curved but separate from the rest of the container, so that the covers 20 and 21 and this back wall 15 may be preliminarily assembled and then covered with a single length of the leather-like facing, and which assembly thus faced, may then be attached to the walls 11 and 12 in the manner already indicated.

In this manner further, I am enabled to have these closure members 20 and 21 extend beyond the walls 10, 11 and 12 so that the simulation to a book is carried out very effectively.

Having now described my invention and illustrated its use, what I claim as new and desire to secure by Letters Patent is—

1. A device for effectively advertising the slogan "Shave and Save", said device comprising a container for a shaving implement and a money container fixedly associated therewith, whereby a person using the shaving implement so contained will have his attention centered on the saving feature, thus most effectively advertising the "Shave and Save" feature of self-shaving.

2. In a device of the character described, in combination a container, comprising side walls, a front wall and a rear wall, means for dividing the space between the walls into two compartments arranged one to the side of the other, a closure for each compartment pivoted to the opposite edges of the rear wall, the whole being constructed and arranged to simulate a book, the closure members extending beyond the walls to cause them to simulate the covers of a book.

3. In a device of the character described, in combination a container, comprising side walls, a front wall and a rear wall, means for dividing the space between the walls into two compartments arranged one to the side of the other, a closure for each compartment pivoted to the opposite edge of the rear wall, the whole being constructed and arranged to

simulate a book, the closure members extending beyond the walls to cause them to simulate the covers of a book, said dividing means comprising an integral member having a vertical wall, and horizontal walls extending in opposite directions from the opposite ends thereof.

4. In a device of the character described, in combination, a container, straps projecting inwardly and spaced from the rear wall thereof, a closure for the container having lugs projecting into the space between the strap and the rear wall, said strap being bent upwardly, whereby an additional increment of movement is permitted the closure so as to permit it to be moved into the plane of the rear wall.

5. In a device of the character described, in combination, a container, straps projecting inwardly from the rear wall thereof, a closure for the container having lugs received between the rear wall and the straps, the closure being made of yieldable material, and the parts being so arranged and constructed that the closure when moved to fully closed position, will first move to an initial position in which it is slightly open, and upon the continued application of pressure to move it to fully closed position, it will be slightly distorted, whereby when released from its fully closed position, the closure will automatically assume a partly open position.

6. In a device of the character described, in combination, a container, comprising parallel side walls and a front wall made of

a single stamping, and a rear wall made separable therefrom and adapted to be attached thereto, and closure members pivoted to said rear wall, whereby the rear wall and the closure members can be assembled as a unit and faced with material as a whole and then assembled with the other three walls.

7. In a device of the character described, in combination, a container, comprising side walls, a front wall and a rear wall, the front wall having flanges projecting inwardly from the opposite edges thereof, a latch bolt received between said flanges for sliding movement along the front, and having flanges projecting from its opposite edges positioned adjacent the flanges of the front wall, and lugs projecting from the flanges of the latch bolt and serving as part of the means for locking a closure in position.

8. A container of the character described, said container being made up of separable units, one unit being in the form of a single stamping forming three adjacent walls of the container, and the other unit comprising the rear fourth wall of the container and adapted to be attached to the first unit to form the rear closure wall of the container and closure members pivoted to said rear wall to complete the container closure, whereby the rear wall and the closure members can be assembled as a unit and faced with material as a whole and then assembled with the other three walls.

In witness whereof, I have hereunto signed my name.

JOSEPH KAUFMAN.
